COMBINATION CLOTHES HAMPER, REFUSE CONTAINER, COOKIE JAR, OR SIMILAR ARTICLE

Natale J. Goss, Chicago, Ill.

Application April 7, 1959, Serial No. 55,394

Term of patent 14 years

(Cl. D58—25)

Fig. 1 is a perspective view of a combination clothes hamper, refuse container, cookie jar, or similar article, showing my new design;

Fig. 2 is a front elevational view thereof;

Fig. 3 is a side elevational view, taken from the left side of Fig. 2;

Fig. 4 is a rear elevational view;

Fig. 5 is a view of the top portion thereof, taken along the line 5—5 of Fig. 3.

The appearance of the side opposite that of Fig. 3 is substantially a mirror image thereof.

I claim:

The ornamental design for a combination clothes hamper, refuse container, cookie jar, or similar article, substantially as shown and described.
